CLOSURE CAP FOR A JAR OR THE LIKE

Lincoln A. Warrell, Mount Holly Springs, Pa., assignor to Pennsylvania Dutch Co., Inc., a corporation of Delaware

Filed May 7, 1968, Ser. No. 11,814

Term of patent 14 years

Int. Cl. D9—99

U.S. Cl. D9—268

FIG. 1.

FIG. 2.

FIG. 3.

FIG. 1 is a top plan view of a closure cap for a jar or the like, showing my new design;

FIG. 2 is a side elevational view; and

FIG. 3 is a bottom plan view thereof.

The essential features of the design resides in the particular ornamentation applied to the top surface of the closure cap.

I claim:

The ornamental design for a closure cap for a jar or the like, as shown and described.
